UNITED STATES PATENT OFFICE

HARVEY J. STEVENSON AND MERRILL KESSLER, OF LOS ANGELES, CALIFORNIA, ASSIGNEES TO NATIONAL MANICURING MACHINE COMPANY, OF LOS ANGELES, CALIFORNIA, A CORPORATION OF DELAWARE

MANICURING INSTRUMENT

Application filed November 5, 1928. Serial No. 317,276.

Our invention relates to manicuring instruments, and more particularly to power-driven instruments and the means for interchangeably connecting and driving the different instruments.

These various instruments are used at the end of a flexible shaft, driven from a motor, and one of the objects of our invention is to provide a flexible shaft in which the inner shaft is so connected through the outer casing that any pull on said instrument as it is being manipulated is not through the outer flexible casing, but is direct through the inner or drive shaft proper and which is directly connected to the motor shaft.

Another object of our invention is to provide improved means for detachably securing the instruments to the drive shaft so they can be readily interchanged.

Another object is to provide improved constructions in the instruments which are used with the flexible drive shaft, whereby to give greater efficiency from said instruments with less chance for possible injury to the hand.

In order to more fully explain our invention, we have shown one practical embodiment thereof on the accompanying sheet of drawings, which we will now describe.

Figure 1 is an enlarged side elevation of a flexible shaft, partly in longitudinal section to show the inner parts and connections of the complete outfit, less the motor:

Figure 2 is a cross sectional view taken on line 2-2 of Fig. 1;

Figure 3 is a side view of an abrading instrument, partly in section;

Figure 4 is a left end view thereof;

Figure 5 is a polishing instrument, partly in section.

Referring now in detail to the drawings, 6 designates a drive shaft, provided at one end with a head 7, adapted to be screwed on to the motor shaft by which it is driven. The other end of said drive shaft 6 is provided with a screw socket 8, to receive an interlocking drive element 9, having a bearing collar or flange 9' and an angular extension 9", adapted to interfit with the various instruments to be used.

An outer casing 10, of flexible construc-

tion encloses said shaft, said casing being provided at one end with an attaching head 11, adapted to be secured to the body of the motor (not shown), and with a coiled wire 12, extended a short distance from said head 11, to give protection to the flexible casing and prevent too short bend. The other end of said flexible casing 10, is provided with a coupling element 13, secured to said casing in any desirable manner, and there is also provided a second coil of wire 14, to prevent too short bend of the flexible casing 10, and shaft 6.

The head 7, of the drive shaft 6, it will be noted has a bearing against the inside of the head 11, as at 7', which also serves as an anchorage for any pull which might be applied to the outer end of said drive shaft 6. An intermediate member 15, is connected with the coupling element 13, as by screw connection, and is provided internally with a shoulder or flange 15', through which the interlocking drive element 9 is inserted to connect with the end of the drive shaft 6, and against which the collar 9' of said element bears, so that any pull on said intermediate element, from the instrument, would be applied through said collar 9' to the drive shaft 6, direct, thus eliminating possible pull on the flexible outer casing 10, and making sure that any pull at the instrument end of the driving connection would be applied to the inner drive shaft 6, instead of the flexible outer casing 10, by reason of the bearing at 7', and at 15', as will be clear from the drawings, Fig. 1.

The intermediate member 15, is internally threaded at its open end, as at 15" to receive the shank of the instrument to be used therewith. Each instrument to be attached to said intermediate member has a body portion, designated 16, with a threaded shank 16', adapted to fit into said intermediate member 15, as will be clear from Fig. 1, where one instrument is adjacent, ready to be inserted. The instrument proper, that is the revolving part in each case, has a shaft 17, provided with an angular socket 17', adapted to interfit with the extension 9", with a telescoping fit, whereby said shaft and

instrument are directly driven by the drive shaft 6, through the connections described.

Referring to Fig. 1, the instrument is shown as a conical point, with spiraled holding means for holding a wad of cotton thereon, said conical spiraled point being designated 18, and having a threaded shank 18' to screw into the shaft 17, as shown, with an interfitting joint at 18^a over the end of the body 16, to prevent the cotton from getting into the joint. The conical spiraled point is thus driven from the shaft 17, and its connections through the main drive shaft 6 to the motor shaft.

15 In Fig. 3, we have shown the instrument proper as comprising a disc 19, having its outer face concaved or dished to receive a disc of sand paper 20, or other similar abrading material, to seat therein so that the 20 rounded, smooth edge of said disc 19, overlaps said sand paper and thus makes it impossible for it to accidentally cut the flesh at its edge. The shaft 19' of said disc 19, screws into the shaft 17, as shown. The sand paper 25 20 is held in place by means of a screw 21, and can be interchanged or replaced when desired. The face of the said paper is held against the edge of the finger in the usual usage thereof.

30 In Fig. 5, we have shown a polishing instrument which consists of a shaft 22, with its end threaded, as at 22' and adapted to screw into the shaft 23, in the body 16, with a concaved disc portion 22^a on said shaft 22, with 35 its edges formed into teeth, and with rubber, or other body 24 on said shaft 22, with a holding disc threaded on the outer end of said shaft 22, said holding disc being designated 25. Said cork or body 24, is shown 40 covered with chamois 26, or other suitable covering and polishing material, stretched over the body and tucked into the opposed discs 22^a and 25, and there held until it is desired to replace it with a fresh piece.

45 Each of these instruments is adapted to be readily connected with the intermediate member 15, in the threaded open end 15^a, and to have its driving shaft interfit or interlock with the driving extension 9^a of the 50 interlocking driving element, which not only drives the various instruments by means of its telescoping fit therewith, but also so anchors the drive shaft 6, that any pull on the instrument end, instead of being transmitted 55 through the outer casing, is transmitted to the inner drive shaft 6, as hereinbefore described.

We do not limit our invention to all the details shown and described for illustrative purposes, except as we may be limited by the hereto appended claims.

We claim:

1. In a manicuring apparatus, a drive shaft, an outer casing, both being flexible, 65 said drive shaft being operable in said outer

casing, said drive shaft at its opposite ends being anchored in said outer casing to take any pull strain applied to said outer casing, whereby pulling strain on the instrument end of said outer casing will not stretch the same, an instrument detachably connected with said outer casing, with driving connections from the drive shaft to the instrument. 70

2. A manicuring instrument including a flexible outer casing, a drive shaft therein, said drive shaft having a head abutting inwardly against a part of said outer casing and at its opposite end, said drive shaft being provided with an interlocking element abutting inwardly against a part of said outer casing, and adapted to prevent stretching of said outer casing and to take the strain of pull on the instrument end of said outer casing, an instrument adapted to be detachably used in the end of said outer casing, and interconnecting driving connections from said interlocking element and said instrument for driving the latter from said drive shaft. 80

3. In an instrument of the character referred to, in combination, an inner, flexible drive shaft having a head of larger diameter with shoulder and a threaded socket in its end, an outer flexible casing therefor and having a head within which said shaft head fits with its shoulder abutting against the inner part of said head on said casing, an interlocking element screwed into the opposite end of said drive shaft and having an enlarged part abutting inwardly against a part in said outer casing, whereby said drive shaft takes any pull strain on said outer casing and prevents its stretching, an instrument detachable to said outer casing, and interfitting, driving connections between said instrument proper and said interlocking element, whereby the latter is driven from said drive shaft. 90

4. In combination, an outer flexible casing tube, an inner drive shaft, abutment means at the opposite ends of said drive shaft within said casing to take the strain of pull on said casing tube, an instrument detachable to said outer casing tube, and driving connections from the drive shaft within said casing tube to said instrument. 100

5. In combination, an outer flexible casing tube, an inner drive shaft, abutment means between the opposite ends of said drive shaft and the inside of said casing tube to take longitudinal strain on said casing tube, whereby to prevent stretching of the latter, an instrument proper having a conical point with spiraled means thereon to hold cotton or the like, and adapted to be operatively connected with said casing tube and said drive shaft. 110

6. In combination, a flexible casing tube, a drive shaft therein, abutment means on said drive shaft within said casing tube and abutting inwardly at opposite ends against portions of said casing tube, whereby to prevent 120 130

stretching of said casing tube, an instrument having a part detachably connected with said casing tube and an instrument proper operatively connected therein with said drive shaft, 5 whereby said instrument is driven from said drive shaft.

7. In combination, a flexible outer tube, a drive shaft therein, anchor means at the opposite ends of the drive shaft to abut inwardly against the inner portions of said outer tube and to take pull strain from said outer tube, and a manicuring instrument detachable from said outer tube, said instrument comprising a conical point provided with 10 spiraled means from its larger end to its point for holding material thereon while revolving, means for connecting the body of the instrument to said outer tube, and means for connecting the conical point to said drive shaft 15 20 within said outer tube for driving the conical point.

Signed at Los Angeles, Los Angeles County, California, this 29th day of October, 1928.
